UNITED STATES PATENT OFFICE.

WILLIAM M. DANA, OF RIPON, WISCONSIN.

WINDOW-SCREEN.

SPECIFICATION forming part of Letters Patent No. 329,287, dated October 27, 1885.

Application filed July 15, 1885. Serial No. 171,686. (No model.)

To all whom it may concern:

Be it known that I, WILLIAM M. DANA, of Ripon, county of Fond du Lac, State of Wisconsin, have invented a new and useful Improvement in Window-Screens, of which the following is a full, clear, and exact description, reference being had to the accompanying drawings, making part of this specification.

My invention relates to an improvement in window-screens; and it consists in the peculiar construction and combination of devices that will be more fully set forth hereinafter, and particularly pointed out in the claims.

In the accompanying drawings, Figure 1 is an elevation of a window-screen embodying my invention applied to a window. Fig. 2 is a detail transverse sectional view taken on the line *xx* of Fig. 1. Fig. 3 is a detail vertical sectional view taken on the line *zz* of Fig. 1.

20 A represents the frame of the screen, which consists of the side rails, *a*, the top rail, *b*, and the bottom rail, *c*. A wire-gauze, *d*, is stretched across the frame and secured at its edges to the rails thereof, as shown. The side rails 25 are rabbeted on their inner sides, as at *e*, and in these recesses are fitted extension-strips *B*. The side strips, *B*, can be moved in or out to fit the screen in the window-frame below the upper sash, thus enabling the lower sash to 30 be raised or lowered without disturbing the screen.

C represents headed bolts that pass through openings from the inner sides of the side rails, *a*, and are provided with screw-threads on 35 their outer ends, which are screwed into the inner sides of the extension-strips *B*. Coiled springs *D* are placed on these bolts, and bear between the extension-strips and the side rails, so as to press the strips out against the inner 40 sides of the frame, and thereby secure the screen tightly therein. The inner ends of the springs *D* rest in openings *f* in the outer sides of the side rails, so as to allow the strips *B* to be pressed inwardly, in order to raise the 45 screen or remove it from the window-frame. Knobs *E* are secured to the strips, as shown, by means of which the strips may be drawn inwardly when it is desired to remove the screen from the window.

50 To the upper side of the top rail, *b*, is secured a rubber strip, *f*, that extends laterally beyond the inner side of the screen and bears against the outer side of the bottom rail of the top sash when the screen is in place in the 55 window-frame, and thereby makes a tight

joint between the screen and the top sash, to prevent insects from entering at that point. A U-shaped keeper, *G*, is pivoted to the top rail of the screen by an eye-screw, *g*, through the eye of which passes one arm of the keeper, the screw being embedded in the top rail of the screen. This keeper can be swung outwardly from the inner side of the screen and placed under the lower rail of the upper sash, the arms of the keeper embracing opposite 65 sides thereof, so as to secure the screen firmly to the upper sash without marring or injury to the latter. As the screen is secured in the frame below the top sash, the lower sash may be raised or lowered at will without the necessity of removing the screen. The extension-strips may also be applied to doors, to cause the latter to fit tightly in their frames when closed, and thus answer the purposes of a weather-strip.

70 A window-screen constructed as hereinbefore described is light, cheap, and simple, is easily placed in the window-frame and removed therefrom, and is not likely to get out of order.

75 I am aware that window-screens have been heretofore constructed with side extension-strips and springs bearing against said strips, and this, broadly, I disclaim.

80 I am also aware that window-screens have been heretofore provided at their upper sides with laterally-projecting rubber strips to bear against the window-sash, and this I disclaim.

Having thus described my invention, I claim—

90 1. The combination, with a window-screen, of the U-shaped keeper *G*, pivoted to the screen at its upper side, to secure said screen to the lower side of the upper window-sash, substantially as described.

95 2. A window-screen adapted to fit in a window-frame below the upper sash, and having the laterally-extended rubber strip *f* at the upper side of the screen to bear against the upper sash to form a tight joint therewith, and the U-shaped keepers pivoted to the screen to embrace the lower side of the upper sash and secure the screen thereto, substantially as described.

100 In testimony whereof I have hereunto set my hand this 1st day of July, A. D. 1885.

WILLIAM M. DANA.
